OF SEATTLE, WASHINGTON.

ROTARY PUMP.

987,711.

Specification of Letters Patent. Patented Mar. 28, 1911.

Application filed May 6, 1910. Serial No. 559,684.

To all whom it may concern:

Be it known that I, ADELBERT FOURNIER, a citizen of the United States, and a resident of Sprague, in the county of Lincoln and 5 State of Washington, have invented a new and Improved Rotary Pump, of which the following is a full, clear, and exact description.

The object of the invention is to provide 10 a new and improved rotary pump, designed for general pumping purposes and arranged to utilize the driving power to the fullest advantage, with a view to produce a continuous and forceful stream.

15 For the purpose mentioned, use is made of a cylinder having an inlet and an outlet, and in which is eccentrically mounted a ring-shaped piston operating in conjunction with a sliding abutment arranged in the cylinder 20 between the inlet and the outlet, the abutment being connected with and operating in conjunction with the said piston, and the latter being rolled off on the inner surface of the said cylinder by the action of rollers 25 mounted on arms attached to a driving shaft, eccentrically passing through the said piston and axially through the said cylinder.

A practical embodiment of the invention 30 is represented in the accompanying drawings forming a part of this specification, in which similar characters of reference indicate corresponding parts in all the views.

Figure 1 is a cross section of the rotary pump on the line 1—1 of Fig. 2; Fig. 2 is a 35 longitudinal central section of the same; Fig. 3 is an inverted sectional plan view of the same, on the line 3—3 of Fig. 1; Fig. 4 is an enlarged perspective view of the abutment; and Fig. 5 is a like view of one of the 40 connecting slides for connecting the piston with the abutment.

On a suitably constructed base A is mounted a cylinder B, provided with an inlet C and an outlet D, opening tangentially into 45 the cylinder B, as plainly indicated in Fig. 1. A ring-shaped piston E is mounted to roll over on the inner surface of the cylinder B, and in order to actuate this piston the following arrangement is made: The driving 50 shaft F extends axially through the cylinder B and eccentrically through the piston E, and one end of the said driving shaft F is journaled in a bearing B' formed on or attached to the cylinder head B² (see Fig. 2), 55 and the opposite end of the shaft F extends

through a stuffing box B³ held on the cylinder head B⁴. On the shaft F within the piston E are secured arms G, by the use of keys F' or other suitable means, and on the said arms G are adjustably secured eye-bolts G' carrying a rod G², on which are mounted rollers H in contact with the inner surface of the piston E. When the shaft F is rotated in the direction of the arrow a', then the rollers H acting on the inner surface of the piston E cause the latter to roll off on the inner surface of the cylinder B, in the direction of the arrow a', to produce a vacuum on the inlet side of the cylinder for drawing in the liquid through the inlet C and to force the drawn in liquid out through the outlet D.

Between the inlet C and the outlet D is formed an abutment chamber B⁵, in which is mounted to slide an abutment I in engagement with the peripheral surface of the piston E, so as to separate the inlet side of the cylinder from the outlet side, as will be readily understood by reference to Fig. 1. The abutment I is pressed on at the top by the middle portion of a flat spring J, engaging with its ends the lugs K' of slides K, mounted to slide in grooves B⁶, formed in the cylinder heads B² and B⁴, and opening into the sides of the abutment chamber B⁵. The lower ends of the slides K are provided with steps K², engaging the sides of the piston E, so that when the latter rolls around in the cylinder B, the abutment I is caused to slide up and down with the piston E, as the latter travels around in the cylinder B. By having the spring J interposed between the abutment I and the slides K, the said abutment is yieldingly mounted, and hence always is pressed in contact with the peripheral surface of the piston E, to prevent leakage from the inlet side of the cylinder to the outlet side thereof and vice versa. As shown in Figs. 1 and 3, the thickness of the abutment I is somewhat less than the width 100 of the abutment chamber B⁵, so that the latter opens at all times into the cylinder B, to allow the liquid to pass into the said abutment chamber B⁵, to insure an easy sliding of the abutment I at the time the pump is 105 running.

It is understood that when the pump is running, the pressure on the outlet side of the cylinder B, holds the abutment I against the right-hand wall of the abutment chain- 110

ber B⁵; in case the inlet and outlet are reversed, then the abutment I is shifted over onto the left-hand wall of the abutment chamber. Now as the slides K move in 5 guideways B⁶, as indicated in Figs. 1 and 3, it is evident that the shifting of the abutment I as described and with it that of the spring J, does not disconnect the latter from the slides K, and hence no change is required 10 in running the pump in a reverse direction from the one above described. The top of the abutment chamber B⁵ and the upper ends of the guideways B⁶ are closed by a suitable plate B⁷, bolted or otherwise fastened in place.

When the shaft F is turned in the direction of the arrow a', then the piston E is rolled around in the cylinder B in the same direction, thus causing a suction in the inlet 20 C, to draw the water or liquid into the cylinder B at the right-hand side thereof, and when the piston E passes over the top of the inner surface of the cylinder B and over the entrance of the inlet C into the cylinder, 25 then the water below and in front of the piston E is forced over into the left-hand side of the cylinder and out through the outlet D. It is understood that during the travel of the piston E over the entrance of 30 the inlet C into the cylinder B, the said entrance is not completely closed, but suction is continually produced to draw in water continually, and consequently a continuous stream is forced out of the outlet D. By 35 making the eye bolts G' adjustable in the arms G, the rollers H can always be held in proper contact with the inner surface of the piston E, to hold the outer surface thereof directly opposite the rollers H in contact 40 with the inner surface of the cylinder B.

Having thus described my invention, I claim as new and desire to secure by Letters Patent:

1. A rotary pump, comprising a cylinder 45 having an inlet and an outlet, a ring-shaped piston mounted in the cylinder to roll on the inner surface of the cylinder, an abutment mounted to slide in the said cylinder and connected with the said piston to move in 50 unison with the latter, a driving shaft extending eccentrically through the said piston and axially through the said cylinder, arms on the said driving shaft, rollers in contact with the inner surface of the said piston, 55 and adjustable connections between the rollers and the said arms.

2. A rotary pump, comprising a cylinder having a tangential inlet and a tangential

outlet, a ring-shaped piston mounted to roll off on the inner surface of the said cylinder, 60 means for imparting motion to the said piston, an abutment mounted to slide radially in the said cylinder between the said inlet and the said outlet, a flat spring pressing on the top of the said abutment, and slides 65 having lugs at their upper ends engaged by the ends of said spring, the lower ends of said slides engaging the ring-shaped piston.

3. A rotary pump, comprising a cylinder 70 having a tangential inlet and a tangential outlet, a ring-shaped piston mounted to roll off on the inner surface of the said cylinder, means for imparting motion to the said piston, an abutment mounted to slide radially 75 in the said cylinder between the said inlet and the said outlet, slides engaging the said ring-shaped piston, and a spring interposed between the said slides and the said abutment.

4. A rotary pump, comprising a cylinder 80 having an inlet and an outlet, a ring-shaped piston mounted in the cylinder to roll on the inner surface of the cylinder, an abutment mounted to slide in the said cylinder and connected with the said piston to move 85 in unison with the latter, a driving shaft extending eccentrically through the said piston and axially through the said cylinder, arms on the said driving shaft and provided with adjustable eye bolts, a rod 90 mounted in the eyes of the said bolts, and rollers mounted on the said rod and in contact with the inner surface of the said ring-shaped piston.

5. A rotary pump, comprising a cylinder 95 provided in its heads with guideways, and an abutment chamber connected with the said guideways, a ring-shaped piston mounted to roll off on the inner surface of the said cylinder, means for actuating the said piston, an abutment mounted to slide in the 100 said abutment chamber and of a thickness less than the width of the said abutment chamber to connect the latter at all times with the interior of the said cylinder, slides 105 mounted in the said guideways and engaging the said piston, and a spring interposed between the said slides and the said abutment.

In testimony whereof I have signed my 110 name to this specification in the presence of two subscribing witnesses.

ADELBERT FOURNIER.
